LOUIS H. SCHROEDER, OF WOODHAVEN, NEW YORK, ASSIGNOR TO PROGRESSIVE CORRUGATED PAPER MACHINERY CO. INC., OF BROOKLYN, NEW YORK, A CORPORATION OF NEW YORK

TAPING MACHINE FOR BOX BLANKS

Application filed April 17, 1929. Serial No. 355,753.

The invention relates to a machine for applying tape to the abutting side edges of corrugated paper board box blanks, and more particularly to the operation of pressing the 5 tape in position against such side edges. Machines for the above purpose have been known and used for many years wherein the box blanks, after having had the tape applied along their side edges which are desired to be secured together, are fed between 10 pressure members, usually in the form of traveling conveyor belts, which serve to press the tape in position.

The present invention aims primarily to 15 provide a machine which will more adequately press the tape into proper engagement with the blank and provide a stronger taped box corner on the blank, without injuring or breaking down the structure of the corrugated box board of which the blanks usually 20 are made. In the drawings—

Fig. 1 is a side elevation, with certain parts cut away, of a machine constructed in accordance with the invention.

Fig. 2 is an enlarged vertical section taken 25 on line 2—2 of Fig. 1.

The illustrated machine contains many features, the specific nature of which are not essential to the present invention and which, 30 accordingly, will not be described in detail since machines for performing similar functions have been in practical use for many years.

As shown in Fig. 1, such a machine may 35 have side guides 1 adapted to hold a stack of blanks 2 in position over a table 3, in such a manner that pusher bars 4 carried by traveling belts 5 periodically advance the then lowermost blank of the stack to a mechanism 40 denoted generally by numeral 6, which at the proper time feeds a strip of gummed tape 7 into the path of travel of the blank, as the blank passes between a pair of rolls 8 and 9 carrying traveling conveyor belts 10 and 11 45 which move the taped blank along until it passes out of the machine between similar rolls 12 and 13 at the delivery end of the machine. Suitable devices such as rollers 14, journaled and pivoted arms 15, which are urged toward the blank by spring 16 (Fig.

2), are employed to exert pressure on the taped blank as it passes along. Additional rollers 17 (Fig. 2) also are usually employed on the opposite side of the blank.

I have found that if the tape be pressed 55 against the abutting edges of the blank by a member having a bluntly beveled raised portion on its surface which engages the tape, the tape will be with much greater certainty secured throughout its entire undersurface to 60 the blank (without wrinkles or blisters), and the resulting box corner will be much stronger, and with much reduced likelihood of being crushed. For example, as shown in Fig. 65 2, the conveyor member 11 which engages the integral side 18 of the box blank, is provided with a plane surface 19, which underlies the box blank, as has been standard practice in machines of the above type for ten years or upwards. The conveyor member 10 however which is pressed against the taped surface of the box blank, is provided with a bluntly beveled raised portion 20, which bears 70 against the tape 7, the tape overlying the abutting side edges 21 of the box blank, which 75 form one corner of the completed box. The surfaces 22 and 23 of conveyor member 10 which engage the upper surface of the blank on opposite sides of tape 7, are made plane 80 with the result that the beveled portion 20 of the conveyor member shapes the tape and the edges 21 of the box blank into the cross-sectional form shown in Fig. 2, without however unduly crushing the corrugations of the 85 blank.

While a specific form of the invention has been described it should be understood that many changes may be made therein without departing from its substance as set forth in the appended claims.

I claim:

1. A box blank taping machine having means for advancing a blank to be taped, means for feeding a strip of tape to the path of travel of the blank, and a pair of traveling conveyor members positioned to receive the blank and tape between them and press the tape against the blank, one of said members having a substantially plane surface engageable with one face of the blank and the 100

other of said members also having substantially plane surfaces engageable with the remaining face of the blank on opposite sides of the tape, said last mentioned member having a bluntly beveled raised portion between its above mentioned plane surfaces and engageable with said tape.

5 2. A box blank taping machine having means for advancing a blank to be taped, means for feeding a strip of tape to the path of travel of the blank, and a pressure applying member positioned to bear against the taped side of the blank, said member having a bluntly beveled raised portion positioned to engage the tape.

10 In testimony whereof I have signed my name to this specification.

15 LOUIS H. SCHROEDER.
